(57) **CLAIM**

We claim the ornamental design for a brush for vacuum cleaner, as shown and described.

DESCRIPTION

FIG. 1 is a front perspective view of a brush for vacuum cleaner showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is a rear perspective view thereof; and,

FIG. 9 is a front perspective view of the brush for vacuum cleaner in which a vacuum cleaner in broken lines is provided to illustrate an example environment.

The broken lines in the figures show portions of the brush for vacuum cleaner which form no part of the claimed design.
